UNITED STATES PATENT OFFICE.

EDMUND RANKIN, OF LINCOLN, ILLINOIS.

BOILER-CLEANER.

1,167,520.

Specification of Letters Patent.

Patented Jan. 11, 1916.

Application filed March 24, 1915. Serial No. 16,654.

To all whom it may concern:

Be it known that I, EDMUND RANKIN, a citizen of the United States, residing at Lincoln, in the county of Logan and State of Illinois, have invented certain new and useful Improvements in Boiler-Cleaners, of which the following is a specification.

This invention relates to devices for blowing off or removing scum, dirt, foam, etc., which rises to the surface of the water in steam boilers, and its object is to provide a novel and improved float-controlled skimmer which is so mounted that it remains perfectly level with the surface of the water in all positions of the boiler.

With the hereinstated object in view, the invention consists in a combination and arrangement of parts to be hereinafter described and claimed, reference being had to the accompanying drawing, in which—

Figure 1 is a plan view of the device; Fig. 2 is a longitudinal section of a fragment of a steam boiler showing the device in operative position therein and Fig. 3 is a section on the line 3—3 of Fig. 2.

Referring specifically to the drawing, 5 denotes an ordinary steam boiler in which the skimmer device is mounted, said device comprising a pipe 6 which is float-supported close to the surface of the water in the boiler. A float 7 is located at the outer or free end of the pipe, and adjacent to the inner end of the pipe, on each side thereof, is a float 8. The floats 7 and 8 are suitably connected to the pipe. On one of the end walls of the boiler 5 is connected an outlet pipe or nipple 9 provided on the outside of the boiler with a blow-off valve 10. The skimmer pipe 6 is flexibly connected to the outlet 9 so that it may remain level with the surface of the water in all positions of the boiler. This flexible connection comprises the following parts: To the outlet 9, inside the boiler 5, is connected a hollow coupling member 11 on which is swiveled a second hollow coupling member 12. These two members are connected and held against endwise separation by screws 13 carried by the member 12 and seating at their inner ends in an annular groove 14 in the member 11. The member 12 is free to turn on the member 11 about an axis coinciding with the longitudinal axis of the boiler. To the member 12 is pivoted, to swing vertically, 55 one end of a hollow arm 15 having pivotally

connected to its other end a hollow coupling member 16 which carries the skimmer pipe 6.

The pivotal connection between the member 16 and the arm 15 allows the skimmer pipe 6 to swing vertically relative to the arm, and as said arm is also pivoted to the member 12 to swing vertically, a flexible joint for the skimmer pipe is provided which allows said pipe to remain in horizontal position when the boiler tilts forward or rearward. The double joint allows the skimmer pipe to rise and fall bodily without tilting from the horizontal, and it therefore remains level with the surface of the water at all times. The inlet apertures 17 of the 70 skimmer pipe are at the top, and the floats 7 and 8 will be so adjusted that the pipe is immersed in the water the proper distance to locate the inlets close to the surface of the water to take in the scum, etc., which 75 gathers here. The floats also hold the skimmer pipe so that the inlets remain on top.

The swivel joint between the parts 11 and 12 allows the skimmer pipe 6 to remain level when the boiler tilts sidewise. Locomotive 80 boilers take this position when on a curve, where the curve is higher on one side than at the other. The swivel joint also adapts the device for marine boilers, as the skimmer pipe will stay level no matter how much 85 the vessel pitches. The swivel joint makes the skimmer pipe self-adjusting sidewise, and prevents said pipe from tilting so as to bind the pivot joints between the parts 12, 15 and 16.

Ordinarily, one skimmer pipe is sufficient, the same being mounted midway between the sides of the boiler so as to take the scum, etc., from both sides. On large boilers two or more skimmer pipes may be employed.

I claim:

1. A boiler cleaner comprising an elongated skimmer extending in the direction of the length of the boiler, floats on opposite sides of the skimmer, and a flexible coupling connecting the skimmer to the boiler wall and an outlet, said coupling comprising a member which is swiveled to turn on an axis coinciding with the longitudinal axis of the boiler, a hollow arm pivoted to said member to swing vertically, and a pivotal connection between the arm and the skimmer to allow the latter to swing vertically relative to the arm.

2. A boiler cleaner comprising an elong-

gated skimmer extending in the direction of the length of the boiler, floats on opposite sides of the skimmer, and a flexible coupling connecting the skimmer to the boiler wall
5 and an outlet, said coupling comprising a member connected to the outlet, a member swiveled to said member to turn on an axis coinciding with the longitudinal axis of the boiler, a hollow arm pivoted to the second-
10 mentioned member to swing vertically, a

member pivoted to the arm to swing vertically relative thereto, and a connection between the last-mentioned member and the skimmer.

In testimony whereof, I affix my signature 15
in presence of two witnesses.

EDMUND RANKIN.
